COMBINED DISPLAY AND DISPENSING RACK FOR SUNGLASSES OR THE LIKE

Leslie J. Kovach, Leominster, Mass., assignor to Foster
Grant Co., Inc., Leominster, Mass., a corporation of Delaware

Application December 11, 1957, Serial No. 48,860

Term of patent 14 years

(Cl. D80—10)

The figure is a perspective view of a combined display and dispensing rack for sunglasses or the like showing my new design.

I claim:

The ornamental design for a combined display and dispensing rack for sunglasses or the like, substantially as shown.
